UNITED STATES PATENT OFFICE.

WILLIAM J. MORDEN, OF CHICAGO, ILLINOIS.

TIE-BAR FOR RAILROAD-SWITCHES.

SPECIFICATION forming part of Letters Patent No. 397,090, dated January 29, 1889.

Application filed August 1, 1888. Serial No. 281,650. (No model.)

To all whom it may concern:

Be it known that I, WILLIAM J. MORDEN, a citizen of the United States, residing at Chicago, Illinois, have invented certain new and 5 useful Improvements in Tie-Bars for Railroad-Switches, of which the following is a specification.

My invention relates more particularly to a tie-bar used in connection with split 10 switches, and its object is to provide a tie-bar which will be adequate to tie the rails and so connected to the rails as to be uninjured by an accidental passage of the rail-flange between the movable and the fixed rail, 15 and whereby, also, injury to the point-rail of the switch is avoided.

In carrying out my invention I employ a hanger, which is secured to the movable rails and to which the tie-bar is hinged or pivotally 20 connected, so that, should the rails be forced out of position by the wheels passing through when the switch is improperly set, the rails may rock on their pivotal axis, thereby avoiding any danger of breaking their 25 points and the bending of the tie-bar. I prefer to employ a flat bar and to twist it toward its ends, so as to utilize the maximum strength of the metal and provide for its convenient attachment to the hangers.

30 In the accompanying drawings, Figure 1 shows my improved tie-bar applied to the movable rails of a switch, the bar and hangers being shown in side elevation and the rails in cross-section. Fig. 2 is a side elevation of a section of a rail, showing the hanger and the bar applied thereto, the former in end elevation and the latter in cross-section; and Fig. 3 is a plan view of a section of track and split switch with my tie-bar applied to 40 the movable rails or switch-points.

In said drawings, and referring to Figs. 1 and 2, A represents the rails. The hangers B are adapted, by means of the bolt-flanges b, to be secured rigidly to the web of the rail 45 and in their normal position to rest upon the foot of the rail. Each of the hangers has a pair of downwardly-projecting lugs or ears, b' b', which extend below the bottom of the rail, and between which the edge of the tie-bar is received. The tie-bar C is made from a bar or rod of suitable metal, and I prefer to use a flat bar cut of such length as to project beneath the rails to which it is secured, and when used in a switch it may project beneath the rails of both main and switch 55

tracks, as shown in Fig. 3. In order to secure the maximum strength of the bar and also a convenient method of attaching it to the rails, I prefer to twist its ends one-quarter way around, as at c c, and to enter the ends of the 60 bar edgewise between the lugs b' b' of the hanger, and to secure the bar pivotally to said hanger by means of transverse bolts c' c'. From this it results that the ends of the tie-bar are disposed edgewise with reference to 65 the rails, while the intermediate portion of the bar between the points c c is flatwise with reference to said rails. The ears b' of the hangers will be of such length as, when the tie-bars are secured therein, to bring said 70 bars tightly up against the bottom of the rail.

It is apparent that with the above-described construction and arrangement of parts the rails and tie-bars are pivotally connected or hinged together so that the rails may rock on 75 their pivotal axis. Supposing a train on the rails 4 4^a, Fig. 3, to be passing the switch in a direction from the "heel" to the "points" of the switch-rails and the switch to be set as shown in said figure, it is evident that the 80 flanges of the wheel will force the rail 5 away from the rail 4, and if the connection between the rail 5 and tie-bar were rigid it would result in buckling the tie-bar or in the breaking of the tie-bar or switch-point, or both; 85 but with my improved construction rail 5 will simply rock on the bolt c' and permit the flange to pass through without injury, and thereby many accidents, much delay, and large expense may be avoided. 90

I claim—

1. The combination, in a split switch, with the movable rails, of hangers rigidly secured to said rails and a tie-bar pivotally connecting said hangers, whereby to permit the movable rails to rock upon a horizontal axis, substantially as and for the purpose set forth. 95

2. In a split switch, the combination, with the movable rails A A, of the hangers B B, rigidly secured thereto, and a tie-bar having its 100 ends turned at right angles to its body portion and pivotally connected, respectively, to said hangers, whereby to permit said rails to rock on a horizontal axis, substantially as described.

WILLIAM J. MORDEN.
